UNITED STATES PATENT OFFICE.

JUNIUS P. WHITNEY, OF TYLER, TEXAS.

DESIGN FOR A BADGE.

No. 38,257.

Specification for Design.

Patented Oct. 2, 1906.

Application filed August 16, 1906. Serial No. 330,932. Term of patent 14 years.

To all whom it may concern:

Be it known that I, JUNIUS P. WHITNEY, a citizen of the United States, residing at Tyler, in the county of Smith and State of Texas, have invented a new, original, and ornamental Design for Badges, of which the following is a specification, reference being had to the accompanying drawing; forming part thereof.

The figure is a plan view of a badge, showing my new design.

I claim—
The ornamental design for a badge, as shown.

JUNIUS P. WHITNEY.

In presence of—
C. B. WOOD,
W. H. CALDWELL.
